BOOKHOLDING DEVICE

Application filed November 16, 1931. Serial No. 575,262.

My invention relates to a book-holding device, and more particularly to a device for supporting a book such as a catalog or telephone book.

5 It is one of the objects of my invention to provide a device which supports a book so that when it is not in use it occupies a very small space.

It is a further object of my invention to 10 provide a device of the class described which may be manipulated to support a book in a position in which it may be very easily read.

It is still another object of my invention to provide a book-supporting device which 15 may be moved from its folded or inoperative position to its unfolded or extended position and locked in its extended position with the exertion of very slight physical force.

It is likewise an object of my invention to 20 provide a device of the class described which may be unlocked from its extended position and moved into its folded position with the exertion of slight physical force.

It is still another object of my invention to 25 provide a book-supporting device which may be swung about a vertical axis when it is folded or extended so that when not in use the supporting device and the book may be swung into a position parallel to the vertical 30 surface to which it is secured.

These and other objects and advantages of 35 my invention will be made evident in the following description which may be better understood with reference to the accompanying drawings in which,

Fig. 1 is an elevational view, partially sectioned, of the device of my invention in a folded position.

Fig. 2 is an elevational view, partially sectioned, of the device of my invention in its extended position and supporting a book.

Fig. 3 is an end elevational view, partially sectioned, of my book-supporting device taken as indicated by the line 3—3 of Fig. 2.

45 Fig. 4 is a plan view from below of the device of my invention in extended position.

Referring to the drawings, which are for 50 illustrative purposes only, and particularly to Fig. 1 thereof, the numeral 11 indicates a supporting means or bracket by which the

book-supporting device of my invention is secured to a vertical surface 12 as by screws 13. The bracket 11 is provided with horizontal ears 14 through which bolts 15 are extended and secured by nuts 16. Swingably mounted between the bolts 15 are horizontal flanges 17 which are bent at right angles to a support 18. The support 18 is provided on its forward surface, or that surface opposite to the flanges 17, with retaining flanges 19. As illustrated best in Fig. 3, each of the retaining flanges 19 projects over the surface of the support 18 a short distance and extends substantially throughout the entire length of the support 18.

Formed at each side of the upper end of the support 18 is a pin supporting projection 20. Each of the projections 20 is provided with a substantially elliptical opening 21, the major axis of which is horizontal. Extending through the openings 21 of the two projections 20 is a bolt 22 which is retained in place by a nut 23. The diameter of the bolt 22 is somewhat less than the length of the minor axis of the elliptical opening 21 so that 70 the bolt 22 is horizontally movable relative to the support 18.

Swingably mounted upon the bolt 22 are rearwardly projecting supports 24 formed on each side of a wing supporting member 25 at its upper end. As is well illustrated in Fig. 1, the wing supporting member 25 is somewhat longer than the support 18 and is provided at its lower end with a rearwardly curved portion or handle 26. The wing supporting member 25 is provided with lateral extensions 27 at its sides, each of which is bent to cylindrical form to surround a pin 28.

Supported upon each of the pins 28 is a wing 29 which is provided with extensions 30 complementary to the extensions 27 and likewise bent to a cylindrical form to surround the pin 28. A portion of each of the wings 29 is cut away adjacent the wing supporting member 25, as indicated by the numeral 31 of Fig. 4, 95 so that a coil spring 32 may be disposed around the pin 28 with one of its ends engaging the lower or rearward surface of one of the wings 29, and the other of its ends engaging the upper or outer surface of the 100

wing supporting member 25. The springs 32 serve to resiliently urge the wings 29 to swing about the pin 28 into a closed position. The wings 29 may be of any shape adapted to support the covers of the book to be held by the device. In the embodiment of my invention illustrated in the drawings, the wings 29 are flat members which extend beyond the cover of a book 33 which the device is adapted to support, as illustrated in Fig. 3.

Secured to the outer or lower surface of each of the wings 29 adjacent the center thereof as by welding or soldering, is a small disc 34 provided with a pair of projections 35. Extending through each pair of projections 35 is a pin 36 upon which there is swingably mounted one end of a wing actuating arm 37. The other end of each of the wing actuating arms 37 is swingably mounted upon a pin 38, secured between a pair of projections 39, which is attached as by a bolt 40 to an ear 41 provided by a plate 42.

The plate 42 is attached in any suitable manner to a sliding member or engaging member 43 which is disposed between the support 18 and the flanges 19 so as to be slidable relative to the support 18. As illustrated in the drawings, the ears 41 and the pairs of projections 35 are so related to each other that the wing actuating members 37 swing freely about the pins 36 and 38 when the wings 29 are swung about the pins 28.

Attached to the engaging member 43 a short distance above the plate 42 is a pair of supporting projections 44 to which there is secured a pin 45. Swingably mounted upon the pin 45 is one end of a link 46, the other end of which is swingably mounted upon a pin 47 which is supported between brackets 48 secured to the wing supporting member 25. As the wing supporting member 25 is swung upwardly about the bolt 22 the link 46 causes the engaging member 43 to move upwardly relative to the support 18, and as the wing supporting member 25 is swung downwardly about the bolt 22 the link 46 causes the engaging member 43 to move downwardly relative to the support 18. The wing actuating arms 37 operate to unfold the wings 29 as the wing supporting member 25 is swung upwardly until the wings 29 are almost in the same plane, as illustrated in Fig. 3. Likewise, when the wing supporting member 25 is moved downwardly, the wing actuating members 37 cause the wings 29 to swing about the pins 28 toward each other into their folded position.

The wing supporting member 25 is provided at its upper end and adjacent its lower end with a forwardly or upwardly extending projection 49 through which a rod 50 is extended. The rod 50 is secured in place by a nut 51 so that it is spacially related to the upper surface of the wing supporting member 25, thus permitting the binding of the

book 33 to be placed between the rod 50 and the wing supporting member 25. Likewise provided at the upper end of the wing supporting member 25 is a rearwardly extending projection 52 substantially normal to the plane of the wing supporting member 25. The projection 52 is provided with an engaging finger 53 bent to an acute angle with the projection 52. The finger 53 is adapted to cooperate with the walls of an opening 54 formed in the upper end of the engaging member 43 to retain the engaging member 43 in its uppermost position. As may be seen by reference to Fig. 2, the engaging finger 53 is of such a length that when the wing supporting member 25 is in its most forward position with the bolt 22 at the forward end of the elliptical opening 21, the engaging finger 53 extends through the opening 54 in the engaging member 43 and thus prevents the downward movement of the engaging member 43. Inasmuch as the wing supporting member 25 is prevented by the link 46 from moving downwardly about the bolt 22 while the engaging member 43 is stationary, the extension of the engaging finger 53 through the opening 54 serves to retain the wing supporting member 25 in the position in which it is illustrated in Figs. 2, 3, and 4. The moment of the wing supporting member 25, the wings 29, and the book 33 about the pin 45 causes the wing supporting member 25 to always tend to move to its most forward position with the engaging finger 53 extending through the opening 54. Thus when the wing supporting member 25 is raised to its elevated position, it is automatically locked in this position when the elevating force is relieved from the handle 26. The engaging finger 53 is of such a length that when the wing supporting member 25 is moved to its rearmost position with the bolt 22 at the rearward end of the elliptical opening 21, the engaging finger 53 is withdrawn from contact with the walls of the opening 54 so that the wing supporting member 25 is free to be swung downwardly about the bolt 22.

If it is desired, a reinforcing member 55 may be secured to the forward or outer surface of the engaging member 43 to provide additional rigidity.

The operation of my invention is as follows:

The nut 51 is removed from the rod 50 and the book 33 is disposed upon the wing supporting member 25 and the wings 29. With the book in an open position the rod 50 is secured in place by the nut 51 to prevent the removal of the book 33 from the device. The book 33 is prevented from sliding relative to the device by the two projections 49 provided upon the wing supporting member 25. If the device be in the position in which it is illustrated in Fig. 1, it is evident that the book, the wing supporting

member 25, and the wings 29 may be swung about the bolts 15 so that they are parallel to the vertical surface 12 to which the device is attached, in which position they will 5 occupy very little space. When it is desired to open the book, the book 33, the wing supporting member 25, and the wings 29 may be swung about the bolts 15 until they are in a plane which is not parallel to the 10 vertical surface 12. If now the handle portion 26 of the wing supporting member 25 be grasped and swung upwardly about the bolt 22, the upward movement of the supporting projections 48 of the wing supporting member 25 will cause the engaging member 43 to slide upwardly relative to the support 18. This upward movement of the engaging member 43 and the wings 29 causes the wings 29 to be gradually unfolded. This 15 upward movement of the wing supporting member 25 is continued until it reaches the position in which it is illustrated in Fig. 2, at which time the wings are extended, as illustrated in Fig. 3. As explained hereinbefore, the weight of the book 33, the wing supporting member 25, and the wings 29, acting about the pin 45, causes the wing supporting member 25 to assume its most forward position relative to the support 18 so that the 20 bolt 22 is at the forward end of the elliptical opening 21. Consequently, when the wing supporting member 25 reaches its uppermost position, as illustrated in Fig. 2, and the engaging member 43 is likewise in its 25 uppermost position, as illustrated in the same figure, the engaging member 53 projects through the opening 54 of the engaging member 43 to lock the device in its extended position. Inasmuch as the book is supported in 30 its extended position by three rigid arms, it is apparent that the device of my invention provides ample means for the support of the book in its opened position.

When it is desired to close the book, it is 45 necessary only to grasp the handle portion 26 of the wing supporting member 25 and exert thereon a slight force parallel to the wing supporting member 25 and toward the vertical surface 12. This force causes the 50 wing supporting member 25 to be moved toward the vertical surface 12 and causes the bolt 22 to be moved to the rearward end of the elliptical opening 21. Thus the engaging finger 53 is withdrawn from the opening 54 of the engaging member 43 and the wing supporting member 25 is free to move downwardly about the bolt 22. As the wing supporting member 25 moves downwardly the link 46 moves the engaging member 43 55 downwardly toward the position illustrated in Fig. 1. By virtue of the connection through the actuating arms 37 between the engaging member 43 and the wings 29, this downward movement of the engaging member 43 serves to swing the wings 29 into a

folded position, thus closing the book 33. When the wing supporting member 25 is in its lowermost position, as illustrated in Fig. 1, the wings 29 have folded toward each other a sufficient extent to entirely close the book 33. 70

Inasmuch as the device of my invention containing a book may be swung when not in use into a position parallel to the vertical surface upon which it is supported, it is obvious that the device of my invention occupies extremely small space when not in use. It should likewise be obvious from the foregoing description of the operation of the illustrated embodiment of my invention that my book-supporting device may be moved into and locked in extended position, in which position the book is so supported as to be easily available for reference, and it may be unlocked from its extended position and moved into its closed position by the exertion of slight physical force. 75 80 85

While I have described the illustrated embodiment of my invention as attached to a vertical surface 12, it should be obvious that the bracket 11 may be of such form that the device may be attached to a surface in any other plane. 90

It will be readily apparent to those skilled in this art that there are many changes in the details of construction and relative arrangement of parts which will readily occur to them, and I do not, therefore, desire to be particularly limited to the exact disclosure which I have presented in the specification and drawings for the purpose of illustrating the principles of my invention. I desire only to be limited to the scope of my invention as I have defined it in the appended claims. 95 100 105

I claim as my invention:

1. In a book-holding device, the combination of: a support; a book-supporting member pivoted at its upper end to said support so as to be vertically swingable and horizontally movable relative thereto; an engaging member slidable relative to said support and connected to said book-supporting member so as to be moved toward the upper end of said book-supporting member by the swinging up of said book-supporting member; and an engager adapted for engagement with said engaging member to secure said book-supporting member in extended position, said engaging member being adapted for disengagement from said projection by slight horizontal movement of said book-supporting member relative to said support. 110 115 120

2. In a book-holding device, the combination of: a support; a wing supporting member pivoted at its upper end to said support and vertically swingable relative thereto; a slidable engaging member associated with said support and connected to said wing support so as to be moved upwardly by the outward swing of said wing support; wings piv- 125 130

oted to said wing supporting member and connected to said engaging member so as to be unfolded by the upward movement of said engaging member and folded by its downward movement; and engaging means adapted for engagement with said engaging member in its uppermost position to retain said engaging member stationary, said engaging means being disengaged from said engaging member by the exertion of slight horizontal force on said wing supporting member.

3. In a book-holding device, the combination of: a support; a wing supporting member pivoted at its upper end to said support so as to be vertically swingable relative thereto and horizontally movable a short distance relative thereto; an engaging member slidably associated with said support; connecting means between said engaging member and said wing supporting member for moving said engaging member upwardly when said wing supporting member is swung outwardly; wings pivoted to said wing supporting member; connecting means between said wings and said engaging member for unfolding said wings when said engaging member moves upwardly; and engaging means adjacent the upper end of said support and adapted for engagement with said engaging member when said wing supporting member is at its foremost position.

4. In a book-holding device, the combination of: a support; a wing supporting member pivoted at its upper end to said support so as to be vertically swingable relative thereto and horizontally movable a short distance relative thereto; an engaging member slidably associated with said support; connecting means between said engaging member and said wing supporting member for moving said engaging member upwardly when said wing supporting member is swung outwardly; wings pivoted to said wing supporting member; connecting means between said wings and said engaging member for unfolding said wings when said engaging member moves upwardly; and a projection on the upper end of said wing supporting member and adapted for engagement with said engaging member to restrain its movement when said wing supporting member is at the foremost end of its horizontal movement.

5. In a book-holding device, the combination of: a support; a wing supporting member pivoted at its upper end to said support so as to be vertically swingable relative thereto and horizontally movable a short distance relative thereto; an engaging member slidably associated with said support, said engaging member having an opening adjacent

its upper end; connecting means between said engaging member and said wing supporting member for moving said engaging member upwardly when said wing supporting member is swung outwardly; wings pivoted to said wing supporting member; connecting means between said wings and said engaging member for unfolding said wings when said engaging member moves upwardly; and an engager on the upper end of said wing supporting member adapted to extend through said opening in said engaging member when said engaging member is in its uppermost position and said wing supporting member is in its foremost position, said engaging member being disengaged from said engager by the rearward horizontal movement of said wing supporting member.

6. In a book-supporting device, the combination of: a bracket; a support pivoted to said bracket so as to be horizontally swingable relative thereto; a wing supporting member pivoted to said support so as to be vertically swingable and horizontally movable relative thereto; a sliding member associated with said support so as to be movable parallel to said support, said sliding member having an opening therein; a rigid member connecting said support and said wing supporting member so as to move said sliding member upwardly when said wing supporting member is swung outwardly; wings swingably mounted on said wing supporting member and adapted to support a book; rigid auxiliary members connecting said wings to said sliding member so that said wings are opened when said sliding member is moved upwardly; and a projection on said wing supporting member adapted to extend through said opening in said sliding member when said wing supporting member is in its most forward position and to disengage said sliding member when said wing supporting member is in its most rearward position.

7. In a device of the character described, the combination of: a support; a book rest pivotally connected to said support; and locking means connecting said support and said book rest, said locking means being automatically actuated by the weight of said book rest in operative position to retain said book rest in operative position and being adapted for actuation by a slight force parallel to the axis of said book rest to release said book rest for downward movement.

In testimony whereof, I have hereunto set my hand at Los Angeles, California, this 6th day of November, 1931.

LEONARD M. WEBBER.
